PACKAGING CUSHION OR THE LIKE

William R. Armstrong, Fair Lawn, N.J., assignor to
Sealed Air Corporation, Fair Lawn, N.J.

Filed Feb. 17, 1971, Ser. No. 116,301

Term of patent 14 years

Int. Cl. D9—99

U.S. Cl. D9—294

FIG. 1 is a top perspective view of a packaging cushion or the like showing my new design, it being understood that the cellular material partially shown through the cylindrical cushioning elements extends throughout the same;

FIG. 2 is a perspective view wherein a portion of the supporting surface for the cushioning elements has been moved through an angle of 90° for engagement of the edge of an article being packaged; and

FIG. 3 is a perspective view wherein the supporting surface for the cushioning elements has been folded to provide a corner structure for engagement of a corner of an article being packaged.

The bottom of the packaging cushion or the like as seen in FIG. 1 is plain and unornamented.

I claim:

The ornamental design for a packaging cushion or the like, as shown and described.
